UNITED STATES PATENT OFFICE

RICHARD C. VOGT, OF WEST NEW YORK, NEW JERSEY

CURTAIN ROD

Application filed August 20, 1931. Serial No. 558,258.

Important objects of the present invention are, to provide an improved curtain rod and support therefor, and to provide a curtain rod support designed to firmly hold the rod in operative position and also render it easily mountable and demountable. Other objects of the invention will appear hereinafter.

In the drawings, Fig. 1 is a front view of the upper portion of a window frame with my improved curtain rod and its mounting attached thereto;

Fig. 2 a plan view thereof;

Fig. 3 an enlarged fragmentary section taken on the line 3-3 of Fig. 1;

Fig. 4 a section taken on the line 4-4 of Fig. 5, looking toward the rear face of one of the mounted rods;

Fig. 5 an end view of one of the rod mountings;

Fig. 6 an enlarged transverse section taken on the line 6-6 of Fig. 4;

Fig. 7 an enlarged transverse section taken on the line 7-7 of Fig. 4;

Fig. 8 a detail side view of one of the rod supporting ears showing the manner in which a rod is attached thereto;

Fig. 9 a perspective view of an end of my improved rod; and

Fig. 10 a fragmentary inner face view of another curtain rod.

The curtain rod R is an extensible one comprising two telescoping sections 1 and 2. Each section is formed of a sheet metal strip having its longitudinal margins curled rearward to form straight, hook-like flanges 3 upon the section 1, and similar flanges 4 upon the section 2, slidably fitting within the flanges 3 and adapting the rod to be extended and contracted. Along a portion of their length the flanges 3 have a series of keeper notches 5 of ratchet form. Within the rod is a locking device 6 formed by a resilient wire strand bowed into substantially U form and tending to expand within the rod. The free ends of the wire strand are bent outward for locking engagement with the keeper notches and formed with projecting loops 7 which are manually engageable for compressing the strand out of engagement with the notches. Two tension springs 8 are anchored at one

end to the bend of the U-shaped strand and extend within the flanges 4 of the inner rod section 2. At their opposite ends said springs are anchored to said rod section. The springs are attached to an anchor hook 55 10 which is anchored to an eye 11 struck up from the rod section 2. Said section is normally in endwise thrusting engagement with the outturned ends of the locking device, and the ratchet notches are formed to permit the 60 device to ride over them and shift to the left with reference to Fig. 4. Thereby, the rod may be shortened by merely thrusting the rod section 2 inward along the section 1. The locking device, however, snaps into locking 65 engagement with the notches and prevents extension of the rod except by stretching the springs 8.

The outer end of each rod section has improved means for attaching it to a supporting bracket. This means comprises a resilient wire strand 12 bent into substantially U form. A portion of said strand, including the bend thereof, is disposed within the hook-like edge flanges of a rod section and 70 said flanges are pinched inward, as at 13, to hold the strand in place. The free end portions of the strand form prongs comprising resilient shanks 14 extending straight outward from the end of the rod section, and 75 curled outward in opposite directions at their extremities to form loops 15. These loops serve as anchoring heads for the prongs, as will be described hereinafter. The prongs tend to expand but their expansion is limited 80 by the flanges of the rod section. They are compressible toward each other for mounting and demounting the rod, as will be described.

For supporting the rod upon a window frame F there are two brackets B. These 90 brackets are identical in form and a description of one will suffice for both. The bracket comprises a body made of a single sheet metal blank forming a flat portion 16 having straight parallel edges extending most 95 of its length. At its outer end said flat portion is widened and formed with a pair of spaced, rearwardly turned hooks or barbs 17 for anchoring to an outer side of the window frame. A rod-supporting ear 18 is 100

integrally formed with said flat portion of the bracket between said barbs, and is bent forward. Mounted upon the flat, straight-edge portion of the bracket is a slide 19 also formed of a single sheet metal blank and having rearwardly turned guide flanges 20 engaging the straight edges of the flat body portion and shiftably holding the slide thereon. At its end adjacent the ear 18 the slide has an integral, forwardly turned, rod-supporting ear 21 of less length than ear 18. A tension spring 22 is anchored at one end to an out-struck tongue 23 upon the body of the bracket and adjacent the ear 18. The opposite end 15 of the spring is anchored to the inner end of the slide, and the spring extends through a tubular housing 24 formed by bending the slide outward along a longitudinal medial line. The spring tends to draw the slide outward toward the ear 18. If desired, the slide and spring may be omitted from one of the brackets and the ear 21 may be carried directly by the body of the bracket.

Each of the ears 18 and 21 has a pair of 25 bayonet slots 25 for receiving the projecting shanks of the resilient prongs upon the rod ends. The slots extend rearward from the forward edge of the ear and then vertically in opposite directions to form recesses 30 26 for receiving the prongs. The slotted ear forms two opposed hook-like keepers for holding the prongs, and the hooks are separated by a tongue 27. The entrances of the two slots 25 are materially closer together 35 than the normally expanded prongs and to mount the prongs one of them is first inserted transversely into its keeper recess, as indicated in Fig. 8, and then the prongs are compressed to permit the other prong to pass into its slot to its keeper recess, whereupon the resilient prongs expand into holding engagement in their keepers. The keepers hold the prongs against lateral displacement and the loops 15 engage the ear to anchor the prongs 40 against endwise withdrawal. For the detachment of the prongs from the ears, the rod may be forcibly depressed to bend the lower prongs and shift the upper prongs into register with the entrances of their slots. Then, the rod 45 may be rocked and lifted free of the ears. Or, the loops 15 of the prongs may be grasped for manually compressing them. The tongue 27 limits compression of the prongs.

The drawings show the rod R anchored to 50 the longer ears 18 and another rod R' similarly provided with supporting prongs anchored to the shorter ears 21. The rod R' is similar to the rod R except that the resilient locking device 6 is fixed to the inner rod section 2, instead of anchored thereto by a spring. When the rod R' is anchored in place the tension of the springs 22 holds the barbs 17 of the brackets in anchoring engagement with the window frame. The tension of the 55 springs in the outer rod R also acts to hold

said barbs in anchoring engagement with the window frame. Therefore either rod may be removed without disturbing the bracket anchorages. In mounting the rods they are adjusted to a length somewhat less than the 70 space between their respective supporting ears; the ears 21 are shifted against the resistance of their springs to reach the rod R', and the rod R is stretched against the resistance of its springs to reach the ears 18.

It will be seen that my invention provides a 75 secure support for curtain rods and at the same time enables them to be readily mounted and demounted.

What I claim is:

1. The combination of a curtain rod, a pair of spaced supporting prongs carried by said rod, extending from an end thereof and comprising resilient shanks having enlarged anchoring heads at their outer ends; and a supporting bracket for the rod including a pair of vertically spaced hook-like keepers for the prongs, opening toward each other and having entrance clearance therebetween more contracted than the normally expanded prong shanks, for the transverse insertion of said shanks into the keepers, the prongs being compressible toward each other for insertion and resiliently expansible into holding engagement with the keepers.

2. The combination of a curtain rod; a pair of spaced supporting prongs carried by said rod and comprising resilient shanks extending longitudinally from an end of the rod and having enlarged anchoring heads at their outer ends; and a supporting bracket for the rod including means defining a pair of spaced keeper recesses opening toward each other and clearance for transverse insertion of the prong shanks into said recesses, the prongs being compressible toward each other for insertion into the recesses and resiliently expansible for holding engagement therewith.

3. The combination of a curtain rod; a substantially U-shaped resilient member secured 110 to an end of said rod and forming resilient prongs extending longitudinally from an end of the rod and having enlarged anchoring ends; and a supporting bracket for the rod including means defining a pair of spaced 115 keeper recesses opening toward each other and clearance for transverse insertion of said prongs into said recesses, the prongs being compressible toward each other for insertion into the recesses and resiliently expansible 120 into holding engagement therewith.

4. The combination of a longitudinally extensible curtain rod; a spring carried by said rod and tending to contract it longitudinally; a pair of spaced supporting prongs carried 125 by the rod at each end thereof and comprising resilient shanks extending longitudinally from the rod ends and having enlarged anchoring heads at their outer ends; and a pair of supporting brackets for the rod each in- 130

cluding means defining a pair of opposed keeper recesses opening toward each other and clearance for transverse insertion of said prong shanks into said recesses, the prongs being compressible toward each other for insertion into the recesses and resiliently expansible into holding engagement therewith, and the headed prongs anchoring the rod to the brackets and resisting contraction thereof by said spring.

5. The combination of a longitudinally extensible curtain rod; a spring carried by said rod and tending to contract it longitudinally; a pair of spaced supporting prongs carried by the rod at each end thereof and comprising resilient shanks extending longitudinally from the rod ends and having enlarged anchoring heads at their outer ends; and a pair of supporting brackets for the rod each including means for anchoring to a window frame and means defining a pair of spaced keeper recesses opening toward each other and clearance for transverse insertion of a pair of said prong shanks into said recesses, the prongs being compressible toward each other for insertion into the recesses and resiliently expansible into holding engagement therewith, and the headed prongs anchoring the rod to the brackets and cooperating with said spring to hold the brackets anchored to the window frame.

6. An extensible curtain rod comprising a plurality of rod sections connected together for longitudinal relative shifting; a locking device shiftable longitudinally of the rod; a tension spring extending longitudinally of the rod and anchored at one end to one of the rod sections and at its opposite end to said locking device; and keepers carried by the other rod section at spaced points therealong and releasably and selectively engageable by said locking means for shifting the spring anchorage and varying the rod length, the rod being extensible against the spring resistance when the locking device is locked.

7. An extensible curtain rod comprising a plurality of rod sections connected together for longitudinal relative shifting; a locking device shiftable longitudinally of the rod; a tension spring extending longitudinally of the rod and anchored at one end to one of the rod sections and at its opposite end to said locking device; keepers carried by the other rod section at spaced points therealong and releasably and selectively engageable by said locking means for shifting the spring anchorage and varying the rod length, the rod being extensible against the spring resistance when the locking device is locked; and rod supports anchored to the opposite ends of the rod, anchorable to a window frame and adapted to be held to the frame by the tension of said spring.

8. An extensible curtain rod comprising a plurality of rod sections connected together

for longitudinal relative shifting; a resilient, snap locking device adjustable longitudinally of the rod; a tension spring extending longitudinally of the rod and anchored at one end to one of the rod sections and at its opposite end to said locking device; and keepers of ratchet form carried by the other rod section at spaced points therealong and releasably and selectively engageable by said locking means for shifting the spring anchorage and varying the rod length, the locking device being shiftable inward with said spring-anchored rod section and over said ratchet keepers to shorten the rod and being positively lockable automatically to the keepers to anchor the spring for yieldable resistance to extension of the rod and manually releasable to permit free extension of the rod.

9. The combination of a curtain rod; a pair of spaced supporting prongs carried by said rod and comprising resilient shanks extending longitudinally from an end of the rod and having enlarged anchoring heads at their outer ends; and a supporting bracket for the rod including a forwardly extending ear having bayonet slots with vertically spaced entrance branches extending inward from the forward edge of the ear and keeper branches extending upward and downward in opposite directions, said entrance branches being closer together than the normally expanded prong shanks and said shanks being compressible toward each other for transverse insertion into said slots and resiliently expansible into holding engagement with the keeper branches.

10. The combination of a curtain rod, a pair of spaced, resilient supporting prongs carried by said rod and extending longitudinally from an end thereof; and a supporting bracket for the rod including a pair of vertically spaced hook-like keepers for the prongs opening toward each other and having entrance clearance therebetween more contracted than the normally expanded prong shanks, for the transverse insertion of the prongs into the keepers, the prongs being compressible toward each other for insertion and resiliently expansible into holding engagement with the keepers.

11. A curtain rod supporting bracket comprising a bracket body having means for anchoring engagement with an outer side of a window frame, a curtain rod supporting and endwise anchoring member shiftably mounted upon the bracket body, and a spring carried by the bracket and tending to shift said rod supporting and anchoring member outward longitudinally with respect to a curtain rod anchored to said member, for resiliently anchoring the bracket to the window frame by tension of the rod and resistance of the spring.

12. An extensible curtain rod comprising a plurality of rod sections connected together

for longitudinal relative shifting; a resilient, snap locking device anchored to one of the rod sections; and keepers of ratchet form carried by the other rod section at spaced points therealong and releasably and selectively engageable by said locking means for varying the rod length, the locking device being shiftable inward with the rod section to which it is anchored and over said ratchet keepers to shorten the rod and being positively lockable automatically to the keepers to resist extension of the rod and manually releasable to permit free extension of the rod.

In testimony whereof I hereunto affix my signature.
